UNITED STATES PATENT OFFICE.

JAMES J. MURPHY, OF TERRYVILLE, CONNECTICUT, ASSIGNOR TO EAGLE LOCK CO., OF TERRYVILLE, CONNECTICUT, A CORPORATION.

MULTIPLE-KEY LOCK.

974,693.

Specification of Letters Patent.

Patented Nov. 1, 1910.

Application filed May 9, 1906. Serial No. 315,859.

To all whom it may concern:

Be it known that I, JAMES J. MURPHY, a citizen of the United States, residing at Terryville, in the county of Litchfield and State of Connecticut, have invented a new and useful Improvement in Multiple-Key Locks; and I do hereby declare the following, when taken in connection with the accompanying drawings and the characters of reference marked thereon, to be a full, clear, and exact description of the same, and which said drawings constitute part of this specification, and represent, in—

Figure 1 a perspective view of a lock constructed in accordance with my invention. Fig. 2 a view in rear elevation. Fig. 3 a view of the lock with the cover removed, showing the parts in their locked positions. Fig. 4 a corresponding view showing the parts of the lock in the positions due to them after the guard-key has been operated to throw down the pivotal dog and so unlock the main bolt at the heel thereof. Fig. 5 a corresponding view showing the main bolt in its unlocked position and the secondary bolt in its normal position. Fig. 6 a view of the lock with the cover removed, as well as all of the contained parts except the main bolt and pivotal dog which are shown in their locked positions. Fig. 7 a view of the lock in longitudinal section, taken centrally through the adjusting-eccentric. Fig. 7^a a view in vertical transverse section on the line *a—b* of Fig. 2 to show the relation of the supplemental pin-tumbler lock to the lock-case. Fig. 8 a detached plan view of one of the two-part tumblers with the supplemental part thereof in its locked position. Fig. 9 a corresponding view with the supplemental part in its unlocked position. Fig. 10 a detached plan view of the main part of one of the tumblers. Fig. 11 a corresponding view of the supplemental part of one of the tumblers. Fig. 12 a detached plan view of the secondary bolt. Fig. 13 a view of the guard-key. Fig. 14 a view of a depositor's key. Fig. 15 a view of another depositor's key to which the lock may be set. Fig. 16 a view of the manager's or supplemental-lock key.

My invention relates to an improvement in multiple-key locks of the type shown in U. S. Patent No. 666,697, granted January 29, 1901, on the application of James Roche, 55 the lock of this patent being a simple, com-

pact and convenient lock adapted to be reset to a very considerable range of different keys without removal from place and particularly designed to be used as a safe-deposit lock, though not limited to such use. 60

The special object of the present invention is to preclude the possibility of the surreptitious changing of the combination of such a lock while the box to which it is applied is open by setting its tumblers to a 65 key which would then be kept for future use by the person who wrongfully changed the combination or by some one in league with him. Thus an unscrupulous guard might reset the lock while he was in attendance 70 upon the depositor holding the key to the lock.

With these ends in view, my invention consists in a multiple-key lock, having a two-part lever-tumbler comprising a main part 75 and a supplemental part constructed to be set in a variety of positions with respect to each other for coaction with keys of different bittings, in combination with means for resetting the said tumbler by changing the 80 positions of its parts relative to each other, and a supplemental lock for locking the parts of the tumbler with respect to each other after they have been set.

My invention further consists in a multi- 85 ple-key lock having a plurality of two-part lever-tumblers each comprising a main part and a supplemental part constructed to be set in a variety of positions with respect to each other for coaction with keys of differ- 90 ent bittings, in combination with an adjust- 95 ing-eccentric coating with all of the tumblers for resetting them by changing the positions of their parts relative to each other, and a supplemental lock for locking the ad- justing-eccentric.

My invention further consists in certain details of construction and combinations of parts, as will be hereinafter described, and pointed out in the claims.

In carrying out my invention as herein shown, I employ a plurality of two-part locking-lever tumblers, each consisting of a main part 2 and a supplemental part 3, the main part of each tumbler being centrally 105 cut away to form a deep large notch 4, in which the supplemental part 3 is mainly located. The forward wall of the said notch 4 is formed with serrations 5, which are engaged with and interlocked by correspond- 110

ing serrations 6, formed upon the outer end of the supplemental part 3, which is provided with a key-sweep 7. The rear or inner end of the main part 2 of each tumbler 5 is cut away and reduced to half the thickness of the rest of the part and formed with a circular hole 8, which receives the arbor-like adjusting-eccentric 9, which passes through all of the tumblers, and by means of 10 which the two members of the respective tumblers are moved with respect to each other and unlocked and then after readjustment again moved with respect to each other and locked and rigidly held in their locked 15 positions, all without the removal of the tumblers from the lock. The rear or inner end of each of the supplemental parts 3 of each tumbler is also reduced in thickness to about half of the thickness of the remaining 20 portion of the part and formed with an elongated clearance-opening 10, through which the said eccentric also passes, but which does not act upon the supplemental part on account of the elongated form of this 25 opening. The supplemental parts 3 of all of the tumblers are held against possible end-wise movement under the action of the adjusting-eccentric by means of a retaining-pin 11, which passes through a vertically- 30 elongated slot 12, formed in the supplemental part of each of the tumblers. The main part 2 of each of the tumblers is formed with a stump-slot 13 for the reception of the 35 stump 14, located near the outer end of the main bolt 15, which itself rests upon the bottom of the case 16 of the lock. The supplemental part 3 of each tumbler is formed with a stump-slot 17, opening out of the rear 40 wall of a transversely-arranged stump-opening 18, receiving a stump 19, carried by the secondary or auxiliary bolt 20. The supplemental part 3 of each tumbler is provided with a tumbler-spring 21, while the secondary bolt 20 is furnished with a spring 22 which holds the secondary bolt 20 in its 45 locked position in case the depositor's key 53 should line up all of the tumblers at the time of unlocking the main-bolt 15.

The main bolt 15 is formed with a short 50 guide-pin 23, Fig. 6, entering a guide-slot 24, formed in the secondary bolt, Fig. 12. The said main bolt is also formed with a clearance-slot 25 for the retaining-pin 11 and with a clearance-slot 26 for the adjusting-eccentric 9. It is also formed with a 55 key-sweep 27 with a locking-notch 28, formed in its heel for the reception of the nose of a pivotal dog 29, turning upon a pivot 30, located in the bottom of the case, 60 and thrown into its locked position by a spring 31 which also holds the dog in its unlocked position as shown by broken lines in Fig. 4 of the drawings. This dog is thrown into its unlocked position by means of a pin 32, carried by it and arranged to be engaged

by an operating-bevel 33, formed upon the secondary bolt 20, which is formed with a clearance-slot 35 for the adjusting-eccentric 9, with a key-sweep 36, with a stump-notch 37 for the reception of the stump 14 of the 70 main bolt 15, and with a foot or guide 38. I particularly wish to call attention to the fact that each tumbler as a tumbler is separable between its main-bolt stump-slot and its key-sweep. 75

It will be understood that the main bolt 15 is slid back and forth directly upon the bottom of the lock-case 16 and that the secondary-bolt 20 is adapted to slide back and forth directly upon the said main bolt, while the two-part locking-tumblers are superimposed one upon the other, the lower tumbler of the series resting upon the upper face of the secondary bolt, as shown in Fig. 7. The spring 22 of the bolt 20 exerts a constant 80 effort to maintain the same in its normal or locked position in which its operating bevel 33 is in a position of readiness to coact with the pin 32 of the dog 29 in swinging the dog so as to release and unlock the main bolt, 90 the secondary bolt being moved against the tension of its spring 22 for causing its operating bevel 33 to coact with the pin 32, by means of the guard-key. The lock-case 16 is provided with the usual cover 39, which is 95 furnished with a sleeve 40, inclosing a key-hub 41 of usual construction.

The mechanism thus far described is that of the patent referred to. In order to accomplish the specific object of my present invention, I secure a pinion 42 upon the projecting end of the adjusting-eccentric 9, which extends through the bottom of the lock-case. This pinion 42 meshes into a corresponding pinion 43 non-rotatably mounted 105 upon the projecting outer end of the cylinder or "plug" 44 of a pin-tumbler lock of any approved construction, located in a hole 45 formed for its reception in the cylinder 16. At its rear end the plug 44 is provided 110 with a combined stop and retaining-plate 46 held in place by screws 47. This supplemental lock is operated by an ordinary pin-tumbler lock key 48 which, for convenience, I shall call the "manager's key." This 115 key lifts the pins 49 of the lock into appropriate pin-holes 50 formed in the lock-case and containing spiral springs 51, as shown by Fig. 7a.

The pin-tumbler lock just described is a 120 unitary mechanism organized independently of the other locking mechanism of the lock and forms a supplemental lock for locking the adjusting-eccentric 9 against being turned in either direction for resetting the 125 lock to a new key as might conceivably be done surreptitiously even in the brief interval during which the back of the lock is exposed in use by the opening of the safe-deposit box to which it is applied. It will 130

be understood, of course, that this supplemental lock is never used except when it is desired to reset the lock to a new key. At all other times the main lock is used precisely as if the supplemental lock were not in existence. For the legitimate resetting of the lock to conform to the bittings of another key, the "manager's" key 48 is indispensable for it must be used to unlock the supplemental lock and effect the turning of the eccentric through the medium of the pinions 42 and 43.

In using the main lock, the guard-key 52 is inserted into the lock and engaged with the key-sweeps 7 of the supplemental parts 3 of all of the locking-tumblers, with the effect of lifting the tumblers, so as to bring the stump-slots 17 of the supplemental parts 3 of all of the tumblers into alinement with the stump 19 upon the secondary bolt 20, the key-sweep 36 of which is engaged and the bolt 20 moved from left to right, with the effect of bringing its bevel 33 into engagement with the pin 32 of the pivotal dog, which is forced downward against the tension of its spring 31 and away from the heel-notch 28 in the main bolt 15, the heel of which is now unlocked the spring passing over the dead center to hold the pawl in its downward position. At the termination of the described action of the guard-key 52 it will have the position which is shown in Fig. 4 of the drawings. The guard-key is now removed from the lock and the two-part tumblers allowed to return to their normal positions. The depositor's key is now inserted into the lock and turned, with the effect of engaging the key-sweeps 7 of the supplemental parts 3 of all of the locking-tumblers, which are now again lifted, so as to bring all of their stump-slots 13 into line with the stump 14 of the main bolt 15, which as the key is turned is shot back into its unlocked position, at which time the stump 14 enters the stump-slots 13. As the main bolt 15 is shot back into its unlocked position the tail 29^a of the dog 29 is engaged by the bevel 29^b of the bolt, whereby the dog is swung back again into position for automatic reengagement with the heel of the bolt when the same is shot back into its locked position during the removal of the depositor's key 52 from the lock.

The above description illustrates the ordinary use of the lock. If now it is desired to set the lock to a new depositor's key, such as the key 54, the old depositor's key 53 is first introduced into the lock and turned, so that the two-part tumblers will be lifted for bringing the stump-slots 13 into alinement with the bolt-stump 14, which is thereby permitted to just enter the stump-slots 13, further movement of the main bolt 15 being prevented by the blocking action of the locking-dog 29, which has not been thrown down

out of engagement with the heel of the main bolt 15 by the secondary bolt 20 under the action of the guard-key of which no use is made in resetting the lock to a new depositor's key. While the old depositor's key 53 is in this position, the manager's key 48 is inserted into the cylinder 44 of the supplemental pin-tumbler lock whereby the pins thereof are retired and the cylinder released after which it is turned half a turn. The pinion 43 is correspondingly turned and with it the pinion 44 mounted upon the projecting end of the eccentric 9 which is correspondingly turned. This rotation of the adjusting-eccentric will cause the temporary unlocking of the main and supplemental parts of each tumbler, as shown in Fig. 9, their serrations 5 and 6 being entirely separated from each other. The old key 53 is now removed and the new depositor's key 54 inserted into the lock and turned to lift the supplemental part 3 of each of the locking-tumblers to correspond to the bittings of the key. This result having been effected, the manager's key 48 is turned back half a turn, this movement being communicated through the pinions 43 and 42 to the adjusting-eccentric 9 which is turned back half a turn with the effect of relocking the supplemental parts 2 and 3 of each tumbler again, but this time in their new positions of correspondence to the bittings of the new key 54. The lock is now operated, as before, with the guard-key 52 and the key 54, the key 53 being now useless in connection with the lock.

It will thus be seen that by the addition of a supplemental lock to a lock of the type of the multiple-key lock shown and described in Patent No. 666,697 of January 29, 1901, I am enabled to guard against the surreptitious resetting of the tumblers to a new key during the brief exposure of the back of the lock when the box to which it is applied is open. My design is that the key to the supplemental lock shall be kept by the manager of the safe-deposit vault and that it shall never be brought into use except when he is called upon to produce it by the depositor, who cannot himself use it until the box containing the lock has been opened with the coöperation of the bank officials who keep the guard-key. On the other hand, the bank-officials cannot get at the lock to use the manager's key as the lock must first be unlocked by the use of the depositor's key which the depositor holds.

I claim:

1. In a multiple-key lock, the combination with a plurality of two-part tumblers the respective parts of which are constructed to be reset for coaction with different keys, of means for resetting the said tumblers, and a supplemental pin-tumbler lock for locking the said means.

2. In a multiple-key lock, the combination with a plurality of two-part tumblers the respective parts of which are constructed to be reset for coaction with different keys, of 5 an adjusting eccentric for resetting the said tumblers, a supplemental pin-tumbler lock, and pinions interposed between the eccentric and supplemental lock for locking the said eccentric.
- 10 3. In a multiple-key lock, the combination with the case thereof, of two-part tumblers the respective parts of which are constructed to be re-set for co-action with different keys, an eccentric for resetting the said two-part 15 tumblers, a supplemental pin-tumbler lock mounted in the lock-case, and pinions connecting the supplemental pin-tumbler lock with the said eccentric which is held in its locked position by the said pinions and supplemental pin-tumbler lock.
- 10 4. In a multiple-key lock, the combination with a lock-case, of a plurality of two-part tumblers the respective parts of which are constructed to be reset for co-action with 25 different keys, a main bolt for coaction with the said tumblers, a key-way leading into the lock-case through the front thereof for the reception of a key by which the said two-part tumblers are operated, guard- 30 mechanism coacting with the said main bolt and arranged to be operated by a key also introduced through the front of the said lock-case, tumbler-resetting means, and a supplemental lock located within the said 35 lock-case, connected with the said resetting means for locking the same, and arranged to be operated by means of a key introduced from the back of the said lock-case, whereby the supplemental lock can only be reached 40 for operation when the compartment provided with the lock has been opened by the operation of its two-part tumblers and its guard-mechanism by their respective keys.
- 45 5. In a multiple-key lock, the combination with a lock-case, of a plurality of two-part tumblers the respective parts of which are constructed to be reset for coaction with different keys, a main bolt for coaction with the said tumblers, a key-way leading into 50 the lock-case through the front thereof for the reception of a key by which the said two-part tumblers are operated, guard-mechanism coacting with the main bolt and arranged to be operated by a key introduced 55 through the front of the said lock-case into the key-way aforesaid, tumbler-resetting means, and a supplemental lock located within the said lock-case, connected with the said resetting means for locking the same, 60 and arranged to be operated by means of a key introduced from the back of the said lock-case, whereby the supplemental lock can only be reached for operation when the compartment provided with the lock has been 65 opened by the operation of its two-part tumblers and its guard-mechanism by their respective keys.
6. In a multiple-key lock, the combination with a lock-case, of a plurality of two-part tumblers, the respective parts of which are constructed to be reset for coaction with different keys, a main bolt for coaction with the said tumblers, a key-way leading into the lock-case through the front thereof for the reception of the key by which the said two-part tumblers are operated, guard-mechanism coacting with the main bolt and arranged to be operated by a key also introduced through the front of the said lock-case, tumbler-resetting means, and a self-contained supplemental lock made independent of the said two-part tumblers and guard-mechanism, located within the said lock-case, connected with the said resetting means for locking the same, and having its own key-way, whereby the said resetting means are prevented from being surreptitiously operated, by the supplemental lock.
7. In a multiple-key lock, the combination with a lock-case, of a plurality of two-part tumblers the respective parts of which are constructed to be reset for co-action with different keys, a main bolt for coaction with the said tumblers, a key-way leading into the lock-case through the front thereof for the reception of the key by which the said two-part tumblers are operated, guard-mechanism coacting with the said main-bolt and arranged to be operated by a key also introduced through the front of the said lock-case, tumbler-resetting means, and a self-contained supplemental lock located within the said lock-case, connected with the said resetting means for locking the same, and provided with a key-way leading into it through the back of the lock-case.
8. In a multiple-key lock, the combination with a lock-case; of a plurality of two-part tumblers the respective parts of which are constructed to be reset for coaction with different keys, a main bolt for coaction with the said tumblers, a key-way leading into the lock-case through the front thereof for the reception of a key by which the said two-part tumblers are operated, guard-mechanism coacting with the said main bolt and arranged to be operated by a key also introduced through the front of the said lock-case, tumbler-resetting means, and a supplemental pin-tumbler lock located within the said lock-case and having its plug connected with the said resetting means for locking the same and arranged to be operated by means of a key introduced from the back of the lock-case.
9. In a multiple-key lock, the combination with a lock-case, of a plurality of two-part tumblers the respective parts of which are constructed to be reset for coaction with different keys, a main bolt for coaction with

the said tumblers, a key-way leading into the lock-case through the front thereof for the reception of a key by which the said two-part tumblers are operated, guard-
5 mechanism coacting with the said main bolt and arranged to be operated by a key also introduced through the front of the said lock-case, an eccentric for use in resetting the tumblers, and a supplemental lock con-
10 nected with the said eccentric for locking the same and arranged to be operated by means of a key introduced into it from the back of the said lock-case.

10. In a multiple-key lock, the combination with a lock-case, of a plurality of two-part tumblers the respective parts of which are constructed to be reset for coaction with different keys, a main bolt for coaction with the said tumblers, a key-way leading into the lock-case through the front thereof for the reception of a key by which the said two-part tumblers are operated, guard-
15 mechanism coacting with the said main bolt and arranged to be operated by a key also introduced through the front of the said lock-case, an eccentric for use in resetting the said tumblers, a supplemental pin-tumbler lock located within the said lock-case and arranged to be operated by a key introduced from the back of the said lock-case, a pinion mounted upon the eccentric at the rear end thereof, and a pinion mounted upon the rear end of the plug of the pin-tumbler lock and meshing into the said pinion mounted upon the eccentric which is thus locked by the said supplemental pin-tumbler lock.

11. In a multiple-key lock, the combination with a lock-case, of a plurality of two-part tumblers the respective parts of which are constructed to be reset for coaction with different keys, a main bolt for coaction with the said tumblers, a key-way leading into the lock-case through the front thereof for the reception of a key by which the said two-part tumblers are operated, guard-mechanism coacting with the said main bolt and arranged to be operated by a key also introduced through the front of the said lock-case, an eccentric for use in resetting the said tumblers, a supplemental pin-tumbler lock located within the said lock-case, and pinions connecting the plug of the said pin-tumbler lock with the said eccentric which is locked by the said pin-tumbler lock.

12. In a multiple-key lock, the combination with a lock-case, of a plurality of two-part tumblers the respective parts of which are constructed to be reset for coaction with different keys, a main bolt for coaction with the said tumblers, a key-way leading into the lock-case through the front thereof for the reception of a key by which the said two-part tumblers are operated, guard-mechanism coacting with the said main bolt and arranged to be operated by a key also introduced through the front of the said lock-case, an eccentric for use in resetting the said tumblers, a supplemental pin-tumbler lock for locking the eccentric, a pinion mounted

upon the eccentric, and a pinion mounted upon the plug of the pin-tumbler lock and meshing into the said pinion mounted upon the eccentric.

13. In a multiple-key lock, the combination with a lock-case, of a plurality of two-part tumblers the respective parts of which are constructed to be reset for coaction with different keys, a main bolt for coaction with the said tumblers, a key-way leading into the lock-case through the front thereof for the reception of a key by which the said two-part tumblers are operated, guard-mechanism coacting with the said main bolt and arranged to be operated by a key also introduced through the front of the said lock-case, an eccentric for use in resetting the said tumblers, a supplemental pin-tumbler lock located within the said lock-case and arranged to be operated by a key introduced from the back of the said lock-case, 70 a pinion mounted upon the eccentric at the rear end thereof, and a pinion mounted upon the rear end of the plug of the pin-tumbler lock and meshing into the said pinion mounted upon the eccentric which is thus locked by the said supplemental pin-tumbler lock.

14. In a multiple-key lock, the combination with a lock-case, of a plurality of two-part lever-tumblers the respective parts of which are constructed to be reset for coaction with different keys, a main bolt for coaction with the said tumblers, a key-way leading into the lock-case through the front thereof for the reception of a key by which the said two-part lever tumblers are operated, guard-mechanism coacting with the said main bolt and arranged to be operated by a key also introduced through the front of the said lock-case, tumbler-resetting means, and a supplemental lock located within the said lock-case, connected with the said resetting means for locking the same and arranged to be operated by means of a key introduced from the back of the said lock-case, whereby the supplemental lock can only be reached for operation when the compartment provided with the lock has been opened by the operation of its two-part tumblers and its guard-mechanism by 90 their respective keys.

15. In a multiple-key lock, the combination with a lock-case, of a plurality of two-part lever-tumblers the respective parts of which are constructed to be reset for coaction with different keys, a main bolt for coaction with the said tumblers, a key-way leading into the lock-case through the front thereof for the reception of a key by which the said two-part tumblers are operated, guard-mechanism coacting with the said main-bolt and arranged to be operated by a key also introduced through the front of the said lock-case, an adjusting eccentric for use in resetting the said tumblers, and a sup- 110 120 125 130

plemental lock located within the said lock-case, connected with the said eccentric for locking the same and arranged to be operated by means of a key introduced through 5 a special supplemental lock key-way.

16. In a multiple-key lock, the combination with a lock-case, of a plurality of two-part lever-tumblers the respective parts of which are constructed to be reset for coaction with different keys, a main bolt for coaction with the said tumblers, a key-way leading into the lock-case through the front thereof for the reception of a key by which the said two-part tumblers are operated, 10 15 guard-mechanism coacting with the said main bolt and arranged to be operated by a

key also introduced through the front of the said lock-case, an adjusting eccentric for resetting the said two-part lever-tumblers, a supplemental pin-tumbler lock located within the said lock-case, and pinions connecting the plug of the pin-tumbler lock and the said eccentric, whereby the eccentric is locked by the pin-tumbler lock. 20

In testimony whereof, I have signed this 25 specification in the presence of two subscribing witnesses.

JAMES J. MURPHY.
